PROCESS AND APPARATUS FOR OPERATING TURBINES

Application filed December 20, 1926. Serial No. 155,849.

My invention relates to turbines which are operated by hot combustion gases and some other gaseous fluid of a lower temperature than such combustion gases.

5 It has been proposed to operate a high-pressure turbine by combustion gases issuing from a combustion chamber or explosion chamber and to take the combustion gases exhausting from such high-pressure turbine to a second turbine operating at a lower pressure. Such exhaust gases have temperatures of from 700 to 1000° C. The combustion gases issuing from the high-pressure combustion chamber to operate 10 a gas turbine under substantially constant pressure, have temperatures of the same order or even higher temperatures, especially when the turbine is constructed as a multistage action or reaction turbine in order to obtain as 15 high a thermodynamic efficiency as possible. The materials available hitherto for the construction of turbines have not permitted the turbines to be operated with gases of such high temperatures supplied in a continuous 20 stream. To overcome the difficulties arising from the extreme heat of the combustion gases actuating the turbine, it has been proposed to direct a flow of steam into the turbine simultaneously with the current of combustion gases but at a different point of the turbine. This arrangement of conveying the 25 supply of combustion gases and steam separately to different portions of the turbine presents certain difficulties both as to construction and operation, and it is the object of my present invention to obtain the same advantages while avoiding the difficulties just mentioned. I have found that this can be accomplished by causing the exchange of heat between the combustion gases and the steam to take place, not in the turbine rotor through the medium of the rotor itself, but before such gases and steam are admitted to the turbine blades. By such heat exchange the combustion gases are cooled to a point where their permanent admission to the turbine is permissible, that is to say, their temperature will not be injurious to the turbine even if they are admitted continuously. The drop in temperature 40 may be quite considerable; for instance, the combustion gases may be brought from 1000° C. to 450° C. before they are admitted to the turbine. The question might be asked whether this would not reduce the efficiency of the two media (combustion gases and steam) to such an extent that the advantages of the new method of operation would be nullified or outweighed by too great a loss in the recovery of energy. It has been found, however, that such a loss in thermodynamic 45 efficiency does not occur at all or only to a very slight extent, and my invention therefore enables a considerable improvement to be effected, since the turbine can be operated continuously and safely even with blades 50 made of the usual material, without reducing the degree to which the heat of the combustion gases is utilized.

An explanation of the beneficial results of my invention will now be given with reference to the accompanying drawings, in which Fig. 1 is a diagrammatic elevation with parts in section, illustrating a turbine arrangement embodying my invention; Figs. 2 and 3 illustrate diagrammatically the pressure-volume relationships occurring in plants of the type shown in Fig. 1 for the first case described hereinbelow, wherein both gases or vapors I and II obey the general gas law, Fig. 2 showing the pV diagram for steam and 55 Fig. 3 for highly heated combustion gases; Figs. 4 and 5 show the pressure-volume relationships for the second case described hereinbelow, Fig. 4 showing the pV diagram of the colder of the two heat exchanging bodies 60 as being saturated or moderately superheated steam which no longer follows the general gas law, Fig. 5 showing the corresponding diagram for highly heated combustion gases; Figs. 6 and 7 show the pV diagrams for steam 65 and combustion gases, respectively, when the pressure of the cooler body (e. g. steam) is higher than that of the hotter body; and Fig. 8 is a view similar to Fig. 1 but shows a single turbine to which both of the gaseous media 70 are conducted from the heat-exchanger. In Fig. 1, 10 indicates a combustion or explosion chamber having valves 11, 12 for periodically admitting air and fuel respectively, a suitable ignition device 13 and an outlet valve 14, all 75

of these devices being controlled to secure their proper timing in any well-known manner; see for instance the patent to Holzwarth No. 877,194. 15 indicates a heat-exchange apparatus having two paths, one of which, 16, has its inlet connected as by a pipe 17 with the outlet of the combustion chamber 10, while the inlet of the other path 18 is connected as by a pipe 19 with a boiler or other source of steam. The outlet of the path 16 is connected by a pipe 20 to a combustion gas turbine 21. Similarly, the outlet of the path 18 is connected by a pipe 22 to a steam turbine 23. While I have mentioned steam specifically, this being the medium which I will generally use in practice, I desire it to be understood that I might use as an equivalent therefore, other gaseous media of a temperature lower than that of the combustion gases flowing through the path 16. For the purposes of my invention, as I have found, the cooling medium, that is the steam or its equivalent, should be at the same pressure as the combustion gases or at a higher pressure.

25 The advantages of my invention will be understood from the following considerations, reference being had to the diagrams, Figs. 2 to 5.

Two different gaseous bodies I and II (gases or vapors) having the weights G_I and G_{II} , the same initial pressure p_I and different initial temperatures t_I and t_{II} will, if expanded to the same final or counter-pressure p_2 (for instance, atmospheric pressure), have 30 different temperature drops or capacities for performing work, as indicated by the areas L_I and L_{II} in Figs. 2 and 3 respectively, assuming that as in my invention these two media or bodies perform work independently 35 of each other, for instance, one of them in a steam turbine and the other in a gas turbine. If, however, the hotter body II (for instance, combustion gases) and the relatively cooler body I (for instance, steam) before their 40 ad- 45 mission to the two turbines are caused to pass in heat exchange relation to each other without, however, allowing them to become mixed with each other (as by passing them through the heat exchanger 15 of Fig. 1), the 50 hotter medium II will give off part of its heat to the cooler medium I and therefore the hotter medium, when it reaches the turbine 21, will have a temperature t'_{II} which is lower than its original temperature t_{II} , while the 55 other and cooler medium (for instance, steam), when it reaches the turbine 23, will have a temperature t'_I , which is higher than its original temperature t_I . The heat ex- 60 change has reduced the energy contained in the hotter medium by an amount which we may call ΔL_{II} and has increased the energy contained in the cooler medium by an amount which we may call ΔL_I . It will be evident that as long as ΔL_I is not smaller than ΔL_{II} , 65 the aggregate available energy contained in

the two media has not been reduced by the heat exchange, but has either remained unaltered or has even been increased.

According to the nature of the active media, the amount by which the sum of the values L_I and L_{II} varies (in other words, the difference $\Delta L_I - \Delta L_{II}$) will differ. The thermodynamic calculation yields the following results:

First case: Both active media are in a gaseous state and follow the general law of gases. 75

$$pv = RT$$

In this case the increase in volume ΔV_I which the cooler gas I undergoes by the heat ex- 80 change, is equal to the decrease in volume ΔV_{II} which the warmer gas II undergoes owing to the cooling; thus

$$\Delta V_I = \Delta V_{II}$$

This, however, is correct only when within the temperature limits under consideration, t_I and t'_I or t_{II} and t'_{II} , both gases have equal specific molecular heats C_{pI} and C_{pII} , or equal specific heats K_{pI} and K_{pII} referred to the 85 mass unit of 1 cubic meter at 0° C. and 760 mm. pressure. It can be shown readily that in this case

$$\Delta L_I = \Delta L_{II}$$

In other words, the increase in available energy given to the cooler body by the absorption of heat is equal to the decrease in available energy which the warmer body suffers owing to loss of heat. The heat exchange will therefore not alter the sum of the energies of these two bodies, for instance if both bodies are two-atomic gases and their limit temperatures are not very far apart. 130

If, however, the specific heats K_{pI} and K_{pII} are different (for instance, if II is a two-atomic gas while I is superheated steam or carbonic acid or any combustion gas) then 135 we have the relation

$$\frac{\Delta V_I}{\Delta V_{II}} = \frac{K_{pII}}{K_{pI}}$$

and therefore

$$\Delta V_I = \Delta V_{II} \frac{K_{pII}}{K_{pI}}$$

If, for instance, in this case $K_{pII} > K_{pI}$, then it follows that

$$\Delta V_I > \Delta V_{II}$$

In this case the increase in volume of the 129 colder body I will be greater than the decrease in volume of the warmer body, and from this it follows that

$$\Delta L_I > \Delta L_{II}$$

In this case, therefore, the total available energy would be greater after the exchange of heat than before the same.

Second case: The one (colder) body I is saturated or moderately superheated steam; 130

the other (warmer) body II is any combustion gas. Such steam does not follow the law of gases, and with constant pressure its specific heat varies with the temperature.

5 The combustion gas does, indeed, conform to the law of gases, but its specific heat becomes less with decreasing temperature. In this case the results are obtained by consulting the well-known tables giving the heat of 10 steam and combustion gases, the available energies L_i , L'_i , L_{ii} and L'_{ii} being calculated in the well-known manner.

A special investigation shows that according to the steam pressure and the temperature of the steam and of the combustion gas, the sum of the energies available after the heat exchange, will be greater or smaller than before the heat exchange or stay the same. For instance, with combustion gas derived from oil and having a temperature of 900° C., which is caused to interchange heat with dry saturated steam of a pressure of either 3, 6 or 10 atmospheres until such combustion gas is cooled to 450° C. while the 20 steam is heated up to 400° C., it has been found that the sum of available energy, figured from said initial pressures of 3, 6 or 10 atmospheres to a counter-pressure of 1 atmosphere absolute, is increased by .5% 25 if the initial pressure was 3 atmospheres, while if the initial pressure was 6 atmospheres or 10 atmospheres, said sum is decreased by 2.5% or 4.5% respectively, so that in this case the heat exchange causes a 30 slight reduction of the available energy when relatively high initial pressures are employed.

Conditions are different, however, if we assume that the steam pressure drop is utilized not only down to 1 atmosphere as in the case of combustion gases, but down to a vacuum of say .06 atmospheres absolute as is done in the case of steam turbines. Under this assumption, we shall obtain in each of 45 the three cases referred to above, an increase amounting to 13%, 5.2% and 1.4% respectively. In other words, under these assumptions there will always be a more or less material increase of the entire available energy, 50 as a result of the heat exchange. This may be understood readily by referring to the diagram in Fig. 4, which shows that the surface ΔL_i , representing the additional energy, is continued below the line indicating atmospheric pressure.

Finally, there is also the possibility of having the steam pressure higher during the heat exchange than the pressure of the combustion gases, as indicated in the diagrams, 60 Figs. 6 and 7. Investigation of the conditions obtaining in this case shows, as was to be expected, that in this case also a gain in energy is obtained by the heat exchange, since $\Delta L_i > \Delta L_{ii}$.

65 From the above explanations it will be evi-

dent that the heat contained in the combustion gases and that contained in the steam may be brought into exchange relation to each other in any desired degree, before said media enter the combustion gas turbine and 70 steam turbine respectively, without losing any energy. By proper arrangements, this heat exchange may even result in an increase of energy.

While the combustion gases and the steam 75 have been described as operating on separate turbines or rotors, they might be caused to actuate the same turbine or the same rotor as indicated at 21' in Fig. 8.

I claim:

1. In a turbo-engine, the combination of an explosion chamber adapted to be intermittently charged with an explosive mixture of air and fuel for explosion therein under constant volume, whereby explosion gases of 85 high temperature and pressure are produced, a nozzle valve at the outlet end of such chamber adapted to be opened after each explosion to discharge such gases under pressure, means whereby said gases are expanded without the performance of external work to increase their velocity and simultaneously to reduce their temperature, a heat exchanger, a conduit for leading the high velocity gases into 90 said heat exchanger, a conduit for conducting into the latter a fluid in heat exchange relation with said gases to be heated by the latter, a turbine arrangement, and means for conducting to the latter the cooled gases and 95 the heated fluid to perform work therein. 100

2. The combination with an explosion chamber adapted to be intermittently charged with an explosive mixture of air and fuel for explosion therein under constant volume, whereby explosion gases of high 105 temperature and pressure are produced, said chamber having a nozzle valve at its outlet end adapted to be opened after each explosion to discharge such gases under pressure, of means whereby said gases are expanded without the performance of external work to increase their velocity and simultaneously to reduce their temperature, a heat exchanger connected with said means to receive the expanded, high velocity gases, a conduit for conducting into said heat exchanger a fluid in heat exchange relation with said gases to be heated by the latter, and means for conducting the heated fluid to 110 a place of use. 115
